CHAIR OR THE LIKE

Maxwell E. Pearson, Bally, Pa., assignor to Knoll Associates, Inc., New York, N.Y., a corporation of New York

Filed May 12, 1961, Ser. No. 65,145

Term of patent 14 years

(Cl. D15—1)

FIG. 1 is a side elevational view of a chair or the like embodying my design;

FIG. 2 is a front elevational view of the chair of FIG. 1;

FIG. 3 is a rear quarter perspective view of the chair of FIGS. 1 and 2; and

FIG. 4 is a rear elevation of the chair corresponding to FIGS. 1 and 2.

The design of the chair is characterized by a specific T shaped back support having its narrow edge presented to the rear and with the arms of the T terminating in cylin-

drical bosses which harmonize with cylindrical adjustment knobs, in association with a contoured bottom seat plate, all as shown.

I claim:

The ornamental design for a chair or the like, as shown and described.
